UNITED STATES PATENT OFFICE.

LOUIE CARSON TEMPLE, OF DENVER, COLORADO.

ADJUSTING DEVICE.

1,036,026.

Specification of Letters Patent. Patented Aug. 20, 1912.

Application filed November 4, 1911. Serial No. 658,532.

To all whom it may concern:

Be it known that I, LOUIE C. TEMPLE, a citizen of the United States, residing at Denver, in the county of Denver and State 5 of Colorado, have invented certain new and useful Improvements in Adjusting Devices, of which the following is a specification.

This invention relates to an adjusting device of the type designed to lock two separate parts of a mechanism in any one of a plurality of predetermined positions with relation to each other, and the object of my invention resides in the provision of a device of simple construction in which the adjustment of one of said parts with relation to the other may be readily accomplished without manipulation of the members of which said device is composed, by merely moving the parts to which they are applied 20 to the desired position relative to each other. I attain this object by the mechanism illustrated in the accompanying drawings in the various views of which like parts are similarly designated and in which,

25 Figure 1 represents a plan view of my improved adjusting device, Fig. 2 a longitudinal section taken along the line 2—2; Fig. 1, Fig. 3, a section similar to that shown in Fig. 2 with the adjustable member of the 30 device in the position it occupies during adjustment of the parts, and Fig. 4, a transverse section taken along the line 4—4, Fig. 1.

Referring to the drawings by numerical 35 reference characters, the numerals 2 and 3 designate respectively the two co-operative members of the locking device which are adapted to be attached to the parts of a mechanism which it is desired to adjustably 40 connect, as for example, the body and back of a reclining chair. One of the members 2 comprises a bar 4 which has in its upper edge, a series of teeth 4^a whose faces are formed with an obstructive portion and an 45 inclined portion whereby to permit the movement of a pawl or detent, from any one of the interdental spaces of the bar, into another in one direction only. The member is further provided with a ledge 5 whose 50 upper surface extending substantially parallel to the toothed edge of the bar, has a plurality of low, inclined protuberances or shoulders 6 which are preferably formed by upsetting punched-out portions of the metal 55 of which the member is composed. The ledge constitutes an integral connection be-

tween the bar 3 and a therewith parallel back-plate 7 which provides a ready means for securing the member to the part to which it is applied, and flanges 8 at the ends 60 of the ledge are provided to limit the movement of the locking member, the construction of which will now be described.

The member 3 of the device is composed of a dog 9 which is adapted to be secured at 65 one of its ends to a part of the mechanism to which the invention is applied, and which at its opposite end has a laterally projecting stud 10 which carries a roller 12 which when the members of the device are in the operative 70 positions, occupies one of the interdental spaces of the toothed bar 4. Pivotedly mounted upon the end of the stud 10, is a gravity pawl 13 which, normally, rests upon the shouldered surface of the ledge 5 and 75 which when the pawl 9 is moved along the inclined surfaces of the teeth to adjust its position with relation to the member 2, drags along the surface of the ledge and over the inclined surfaces of the shoulders 80 formed thereon. A pin 14 secured at the end of the stud 10 projects through an elongated notch in the pawl 13, and is provided to limit the movement of the latter about its 85 pivot on the stud.

When the two members of the adjusting device are attached to the parts of the mechanism to which it is applied, they are maintained in a selected position with relation to each other by the engagement of the roller 90 12 on the pawl with any one of the teeth of the bar 4, as is shown in Fig. 2 of the drawings.

To change the position of the part which carries the member 3 of the device in the 95 direction of the arrow *a*, it is but necessary to move the member in this direction, when the roller on the end of the pawl will ride along the inclined face portions of the teeth from one interdental space into the other, 100 while the dog 9 with which it is connected moves about its pivot. If, however, it is desired to change the position of the member 105 3 with relation to the other member of the device in a direction opposite to that indicated by the arrows, it is necessary in order to attain the object of the invention that the roller 12 be lifted free from engagement with the obstructed faces of the teeth on the bar 4 without manipulation of 110 the dog 9. To accomplish this result I have provided the gravity pawl 13 which after

the part to which the dog is attached, has been moved a short distance in the direction of the arrow *a*, will with its free end, engage the adjacent shoulder 6 on the ledge 5 as shown in broken lines in Fig. 3. If the part to which the member 2 is attached, is now moved in the desired direction, the pawl by abutment with the shoulder 6, will turn about its point of contact and thereby 10 lift the roller out of the interdental space on the bar in which it was supported until the pin 14 engages the opposite end of the notch in the pawl, when the dog may be moved in the direction opposite to that indicated by the arrows without engagement 15 with the teeth of the bar until the part to which the member 3 is attached has been brought to the desired position, when by releasing the same, the dog will by gravitational action reassume its former position and carry the roller 12 into engagement 20 with the subjacent tooth of the bar 4.

Having thus described my invention, what I claim is:

- 25 1. In a device of the class described, a member having a series of teeth and a surface extending longitudinal with relation to said series, a member adapted to enter the spaces between said teeth, and a gravity pawl connected with the last mentioned member so as to engage said surface when the members are in their operative position, the said surface having a plurality of shoul-

ders adapted to separately obstruct the movement of said pawl along the same.

2. In a device of the class described, a member having a series of teeth, the faces of which are inclined in one direction, and a surface extending longitudinal with relation to said series, a member adapted to enter the spaces between said teeth, and a gravity pawl connected with the last mentioned member so as to engage said surface when the members are in their operative position, the said surface having a plurality of shoulders adapted to separately obstruct the movement of said pawl along the same, in one direction.

3. In a device of the class described, a member having a series of teeth and a surface extending longitudinally with relation to said series, a member adapted to enter the spaces between said teeth, and a gravity pawl connected with the last mentioned member so as to engage said surface when the members are in their operative position, the said surface having a shoulder adapted to obstruct the movement of said pawl along the same.

In testimony whereof I have affixed my 60 signature in presence of two witnesses.

LOUIE CARSON TEMPLE.
